UNITED STATES PATENT OFFICE

166,849

SPOON HOLDER

George W. Candee, Buena Park, Calif.

Application July 9, 1951, Serial No. 15,800

Term of patent 14 years

(Cl. D44—29)

To all whom it may concern:

Be it known that I, George W. Candee, a citizen of the United States of America, residing in the city of Buena Park, in the county of Los Angeles, State of California, have invented a new, original, and ornamental Design for a Spoon Holder, of which the following is a specification, reference being had to the accompanying drawing, forming a part thereof.

Fig. 1 is a top plan view of the spoon holder showing my new design;

Fig. 2 is a perspective view thereof;

Fig. 3 is a side elevational view of the same; and

Fig. 4 is a front elevational view.

I claim:

The ornamental design for a spoon holder, substantially as shown.

GEORGE W. CANDEE.
